(57) **CLAIM**

The ornamental design for a probe for ultrasound diagnostic apparatus, as shown and described.

DESCRIPTION

FIG. 1 is a perspective view of a probe for ultrasound diagnostic apparatus showing my new design.
FIG. 2 is a front elevational view thereof;
FIG. 3 is a rear elevational view thereof;
FIG. 4 is a left-side elevational view thereof;
FIG. 5 is a right-side elevational view thereof;
FIG. 6 is a top plan view thereof; and,
FIG. 7 is a bottom plan view thereof.
The broken lines are included for the purpose of illustrating portions of the probe for ultrasound diagnostic apparatus that form no part of the claimed design.
